Technical drawing of a mechanical assembly, likely a pump or valve mechanism, showing various parts labeled with numbers 1 through 53. The drawing includes a main vertical assembly with a central shaft, a horizontal rod with a gear-like end, and various connecting rods, levers, and a base plate. The numbers are handwritten in black ink on the lines of the drawing.

UNITED STATES PATENT OFFICE.

PAUL NELSON, OF MORGANTOWN, WEST VIRGINIA, ASSIGNOR OF FORTY-FIVE ONE-HUNDREDTHS TO IRA S. GEMAS AND TEN ONE-HUNDREDTHS TO THOMAS J. MURPHY, BOTH OF MARTINS FERRY, OHIO.

APPARATUS FOR TRIMMING AND PERFORATING SHEET-METAL PACKS.

Application filed November 24, 1923. Serial No. 676,722.

To all whom it may concern:

Be it known that I, PAUL NELSON, a citizen of the United States of America, and resident of Morgantown, county of Monongalia, and State of West Virginia, have invented certain new and useful Improvements in Apparatus for Trimming and Perforating Sheet-Metal Packs, of which the following is a specification.

10 This invention relates to mechanism for trimming the ends of metal sheets and packs preparatory to doubling in the rolling process.

15 The primary object of the invention is to provide an apparatus whereby, in the process of pack-rolling metal sheets, the sheet or pack is trimmed following each rolling of the metal to the elongation required for doubling, and whereby, at the same time, a 20 line of partial severance is produced in the sheet or pack for facilitating the doubling operation.

25 The pack rolling of sheets, as hitherto performed, involves, first, the breaking down of the sheet bars to an elongation which, while varying considerably, is ordinarily about six hundred per cent of the length of the bar. The sheets are then paired, reheated, and again rolled for further elongation, after which they are doubled. The pack is then subjected to a final reheating, after which it is rolled to a final required elongation. In carrying out this prevailing method, the first reheating is rendered necessary only because of the fact that if rolling of the metal in the first rolling operation were continued to effect the elongation which is effected in the second rolling operation, which the temperature of the metal would readily permit, the metal would then be too cold to admit of its being doubled by ordinary means.

30 An object of the present invention is to provide a mechanism which, following elongation of sheets in a single rolling operation to the extent heretofore effected in the second operation, acts to weaken the sheets along the transverse center line thereof so that doubling of the sheets at their then low temperature may readily be effected.

35 A further object is to provide an apparatus of the character mentioned by which

40 packs are readily introduced in position to be trimmed.

45 With these and other objects in view, the invention resides in the features of construction, arrangement of parts and combinations of elements which will hereinafter be described, reference being had to the accompanying drawings, in which—

50 Figure 1 is a front side elevation of the invention;

55 Figure 2 is an end elevation of the same;

60 Figure 3 is a partial central transverse section, showing one of the pack perforating shears, parts of the mechanism being omitted;

65 Figure 4 is a detail vertical section of the shears shown in Fig. 3;

70 Figure 5 is a plan view of the pack as it appears following the first trimming and perforating operation;

75 Figure 6 is a similar view, showing the pack as it appears following the second trimming and perforating operation;

80 Figures 7 and 8 are plan and vertical sectional views, respectively, of the movable blade of the shear employed in the first perforating operation;

85 Figures 9 and 10 are similar views of the stationary blade of said shear;

90 Figures 11 and 12 are similar views of the movable blade of the shear employed in the second perforating operation;

95 Figures 13 and 14 are similar views of the stationary blade of the last mentioned shear;

100 Figures 15 and 16 are enlarged vertical sectional views of the upper and lower blades, respectively, employed in producing short alined perforations or slits;

105 Figure 17 is an enlarged fragmentary view of a sheet, showing the perforations produced by the blades shown in Figs. 15 and 16;

110 Figures 18 and 19 are vertical sectional views of modified forms of upper and lower shear blades;

115 Figure 20 is a view similar to Fig. 17, showing the slits produced by the blades shown in Figs. 18 and 19;

120 Figure 21 is a view of the invention partially in top plan and partially in horizontal section, with parts omitted, showing the pack in the position to which it is auto-

matically shifted following trimming thereof; and

Figure 22 is a transverse section on line 22-22, Fig. 1, with parts omitted, showing the movable blade of an end trimming shear.

Referring to said drawings, 1 indicates the side members and 2 the end members of the horizontal base of a rectangular frame, said base being disposed in a pit 3 of appropriate depth formed in the mill floor. Said frame comprises, additionally, upright corner members 4, and horizontal side and end members 5 and 6, respectively, carried by said corner members at or adjacent to the upper ends of the latter.

Journalized in suitable bearings 7 carried by supporting brackets 8 mounted upon the side members 5 adjacent to each of the opposite ends of the latter is a transverse shaft 9, and mounted upon said shaft adjacent to each of its opposite ends is the upper end of a crank 10 which has pivoted to its lower end the upper end of a link 11. The lower ends of the links of each pair have pivotally attached thereto lugs 12 fixed upon the opposite end portions of the movable member or blade 13 of a shear designed to act upon the adjacent end of a sheet metal pack for trimming said end. Said blade 13, which cooperates with a fixed blade 14 located directly beneath the end portion of the pack when the latter is properly positioned, is vertically movable in suitable guides, as in slots 15 provided therefor in parallel bars 16 which are loosely mounted at their upper ends upon and depend from the adjacent shaft 9.

Journalized in suitable bearings, as 17, carried by the opposite frame members 5 substantially midway between the ends of the frame, is a transverse shaft 18 which has fixed thereon adjacent to each of its opposite ends a crank-arm or disk, as the disk 19, to which is pivoted, as to a wrist pin 20 located eccentrically with respect to the axis of the shaft, the upper end of a depending bar 21, said bar being adapted to be depressed for actuating the movable member or blade of one or the other of two shears as and for a purpose which will hereinafter be explained. Said movable shear members, herein designated 22 and 23, are disposed for sliding movement in suitable guides, as in guide slots 24 and 25 provided therefor in stationary upright bars 26 and 27 carried by the frame. Said movable members 22 and 23 are designed to cooperate respectively with stationary transverse shear members 28 and 29 located directly beneath the middle portion of the pack of sheets when the latter occupies properly placed position with respect to the machine.

Journalized in bearings 30 occupying suitably located positions, as on the side members 1 of the base portion of the frame, inter-

mediate the middle pairs of shears and each of the end pairs of shears is a transverse shaft 31 having thereon rollers 32 which underlie and support the inner end of a longitudinally shiftable table member 33 which has its upper face disposed approximately in the plane of the level of the mill floor 34. The outer end of each table member 33 has hinge-like connection with the lower end portion of the adjacent shear carrying bars 35. Thus, said table members move outward and inward, traveling upon their supporting rollers 32, as said bars are swung outward and inward as and for a purpose to be hereinafter explained.

Disposed for travel in transversely arranged guides 35 located below the floor level, as in channels 36 provided in the bottom of the pit 3 and extending through the mill floor to an appropriate distance in front of the frame of the machine, are slideable bars 37. Carried by the outer end portions of said bars 37 are pack pushers by means of which packs positioned in front of the machine may be moved into operative position with respect to the various shears. While said two pushers may be of any other appropriate form, those herein shown for illustrative purposes consist of one-piece resilient metal bars 38 attached to the outer ends of said bars 37. Each bar 38 inclines upward and inward toward the front side of the frame of the machine and normally presents an inwardly facing shoulder 38a located slightly above the floor level and adapted to lie in abutting engagement with the outer lateral edge of the sheet metal pack which is to be entered in the machine. Inward sliding movement of the sliding bars 37 following the placing of a pack in position on the floor in front of the machine frame, actuates the pusher bars 38 to engage and force said pack inward to proper position upon the table members 33. Such inward sliding movement of the bars 37 is effected by any suitable means, as by lever mechanism including levers 39 fixed on a suitably located rotary shaft 40 carried by the frame. The lower end of each of said levers 39 carries a wrist pin which is engaged with a slot 14 provided in an upright lug 42 carried by the adjacent bar 37. A hand lever 43 fixed on said shaft 40 provides means whereby rotary movement is imparted to the shaft 40, the same being adapted to be swung downward by hand power and engaged with a stationary latch-like retaining member 44 located at a suitable point for securing said parts against return movement.

Coil springs 45 serve to yieldingly support the movable blades 13 of the opposite end shears in elevated position, each of said springs being attached at one end to a substantially upright arm 46 fixed upon the

adjacent shaft 9 and at its opposite end to a suitably located stationary part, as to a bracket 47 carried by the frame. Actuation of said blades 13 is effected against the tension of said springs 45 by power mechanism which includes a power cylinder 48, either operated by steam or compressed air, which has the outer end of its piston rod forming a rack-bar 49. Said rack-bar 10 is engaged with a gear wheel 50 fixed on the shaft 18. Two links or pitmen 51 have pivotal connection with each of the disks 19 at diametrically opposite points, said pitmen extending in opposite directions and 15 having their outer ends pivotally attached to the adjacent opposite crank arms 10. Thus, forward rotary movement imparted to the shaft 18 through the medium of the power cylinder 48, as aforesaid, acts through 20 said pitmen to exert an inwardly directed pull upon said crank arms 10 and, consequently, to actuate the movable blades 13 which are suspended from said crank arms to move downward into cooperative relation 25 to the fixed blades 14 for shearing off, or trimming, the ends of the pack.

Each of the shafts 9 has fixed thereon the outer ends of two convergently related arms 52 which carry upon their meeting inner 30 ends a gear segment 53, the opposing segments being disposed in meshing relation, as shown in Fig. 1. Thus, rotary movement imparted to one of the shafts 9 induces, through the intermediacy of said 35 segments, corresponding movement of the other of said shafts, resulting in the maintenance of the opposite end shears at equal distances from the center or middle of the packs upon which they act.

40 The movable shear blades 22 and 23 are yieldingly supported at opposite ends by coil springs 54 and 55, respectively, attached to the stationary bars 26 and 27 with respect to which said members are slideable. Each 45 of said blades has therein holes or recesses 56 adapted for the reception of the adjacent ends of pins 57 which are carried by and which have their opposite ends projecting on opposite sides of the depending bars 21. 50 In practice, but one of said blades 22 and 23 is actuated at a time according to the character of the perforations to be formed in the middle portion of the pack. When the shear blade 23 is to be actuated, the 55 bars 21 are first thrust by means of a hand lever 58 to position in which their pins 57 seat in the recesses of said blade, following which said bars 21 are actuated by forward rotary movement of the shaft 18 to move 60 downward for thrusting said blade into cooperative relation to the stationary shear member or blade 29. Or, when the blade 22 is to be depressed, said lever 58 is drawn outward to dispose the pins 57 in the recess 65 of said blade 22, which is then actuated

downward as aforesaid. Recesses 59 and 60 provided in the under side of said lever 58 are engaged with a suitably located fixed pin, stud or rod 61 according as the blade 22 or the blade 23 is to be actuated. 70

The shear which includes blades 23 and 29 is located precisely midway between the laterally shiftable end shears and is designed to produce in the middle transverse line of the pack, simultaneously with the 75 trimming of the opposite ends of the pack, a transverse line of narrow slits or perforations whereby the resistance to doubling of the pack along said middle line is overcome to the extent that such pack may 80 be readily doubled by hand even when cold. While various forms of such slits and perforations may be employed, it is at present preferred that slits 62 extend into the pack from each of its opposite lateral edges a 85 distance of from one-fourth to one-third the width of said pack, and that a line of shorter slits 63 be formed intermediate said slits 62, as shown in Fig. 5.

Following doubling of the pack, the latter 90 is reheated and subjected to further rolling which results in elongation of the pack to the extent that a second doubling is required. As a preliminary to such second doubling, the pack is reintroduced in the 95 machine in a position in which its opposite ends are trimmed and a line of perforations, as 64, Fig. 6, is cut across the transverse center line of the pack by the actuation of shear-blade 22. The weakening of 100 the pack which results from the provision of such perforations provides for comparatively easy doubling.

As is obvious, various forms of slits or 105 perforations other than those hereinbefore specifically mentioned may be employed through the provision of different forms of shear blades, as the short straight slits 65, Fig. 17, produced by cooperating blades 66 and 67, respectively, shown in Figs. 15 and 110 16, or the slits 68 having at opposite ends short angularly disposed terminals 68a, Fig. 20, produced by cooperating blades 69 and 70, respectively, shown in Figs. 18 and 19.

For facilitating the proper positioning 115 of the pack, suitable upright stops, as 71, may be positioned as gauges in any of a series of holes 72 provided therefor in the outer end portions of the table members 33.

Following the pack shearing and perforating operation, the movable blade of the perforating shear is elevated to normal position by the thereto-attached springs, and the opposite end shears resume their normal 120 positions, being actuated by the tension springs 45 and the weight of certain of the suspended parts, assisted if and when necessary by power applied by hand, as through a lever 73 pivoted at a convenient point on the frame and having connection through a 125 130

5 pivoted link 74 with one of the gear segments 53. Additionally, a weight 77 may be provided on the end of an upwardly inclined arm 78 fixed on the shaft 18, as shown in Fig. 1, for assisting in restoring parts of the mechanism to normal positions.

10 Upon the release of the hand lever 43 from the retaining member 44, the weight of the depending lever 39 suffices to slide the bars 37 to their outwardly thrust position. At the same time, the weight of a lever 75 pivoted on the frame at a suitable point adjacent to one end of the latter, supplemented by the weight of an end of a thereto-pivoted dog 76 whose free end rests upon the adjacent table member 33 against the inner edge of the pack adjacent to one end of the latter, produces a force which, acting through said dog, results in an end 20 of the pack 77 being pushed outward from the table of the machine to substantially the diagonal position shown in Fig. 21, in which position said pack may be conveniently grasped by a workman for effecting withdrawal of the pack from the machine. It will of course be understood that in entering the pack, the dog 76 and lever 75 are thrust rearward and remain in such position until the pusher bars 38 are withdrawn from engagement with the pack.

30 I have herein illustrated my invention in what I consider to be its simplest form. It will be apparent, however, that various mere mechanical changes in the form and arrangement of some of the parts may readily suggest themselves to persons skilled in the art. I do not therefore desire to limit myself except as may be required by a fair interpretation of the appended claims.

40 What is claimed is—

1. Mechanism for trimming and perforating sheet metal packs, comprising two relatively shiftable pairs of end trimming shears, selective means for producing a transverse line of perforations midway between the ends of the pack to facilitate doubling, and power mechanism for simultaneously actuating said shears and the selected perforating means.

45 2. Mechanism for trimming and perforating sheet metal packs, comprising end-trimming shears, two independent perforating devices arranged substantially midway between said shears, rotary devices whereby said perforating means are actuated selectively, and means intermediate said rotary means and said shears whereby the latter are actuated simultaneously with the selected perforating device, and means whereby said shears may be shifted relatively for trimming packs of different lengths.

50 3. Mechanism for trimming and perforating sheet metal packs, comprising end-trimming shears, perforating means ar-

5 ranged substantially midway between said shears, rotary means whereby said perforating means are actuated, means intermediate said rotary means and said shears whereby the latter are actuated simultaneously with 70 said perforating means, means normally holding said shears in parallel relation, and means for relatively shifting said shears to position the latter for trimming packs of different lengths.

75 4. Mechanism for trimming and perforating sheet metal packs, comprising end-trimming shears, perforating means arranged substantially midway between said shears, rotary means whereby said perforating means are actuated, means intermediate said rotary means and said shears whereby the latter are actuated simultaneously with 80 said perforating means, means normally holding said shears in parallel relation, and means for relatively shifting said shears to position the latter for trimming packs of different lengths, said shifting means including means whereby shifting of said shears is effected simultaneously and 85 throughout corresponding distances.

90 5. Mechanism for trimming and perforating sheet-metal packs comprising a frame, two pairs of shears located adjacent the opposite ends of said frame, each pair of said shears consisting of a stationary member and a member reciprocable relative to said stationary member, relatively shiftable members carrying said stationary shear members and forming guides for said reciprocable shear members, means for shifting said shiftable members whereby they are actuated simultaneously throughout corresponding distances, pack perforating devices intermediate said shears, and means for 95 simultaneously actuating said shears and said perforating devices.

100 6. Mechanism for trimming and perforating sheet-metal packs comprising a frame, two pairs of shears located adjacent the opposite ends of said frame, each pair of said shears consisting of a stationary member and a member reciprocable relative to said stationary member, relatively shiftable members carrying said stationary shear members and forming guides for said reciprocable shear members, means for shifting said shiftable members, means interposed between said shiftable members whereby they are actuated simultaneously throughout corresponding distances; two independent pack perforating devices located intermediate said pair of shears, each including a reciprocable member, an element arranged to engage said devices selectively, power operated means for actuating said element to depress the selected device for perforating the pack, and means intermediate said power operated means and the reciprocable member of each pair of shears whereby the 105 110 115 120 125 130

latter is actuated for effecting trimming of the ends of the pack simultaneously with the perforation thereof.

7. Mechanism for trimming and perforating sheet-metal packs comprising a frame, 5 two pairs of shears located adjacent the opposite ends of said frame, each pair of said shears consisting of a stationary member and a member reciprocable relative to said stationary member, relatively shiftable members carrying said stationary shear members and forming guides for said reciprocable shear members, means for shifting said shiftable members, means interposed between said shiftable members whereby they are actuated simultaneously throughout corresponding distances, pack supporting devices connected to and shiftable with said shiftable members, a pack perforating device arranged intermediate said shears, and power actuated mechanism whereby said shears and said perforating device are simultaneously actuated.

8. Mechanism for trimming and perforating sheet metal packs comprising a frame, two pair of shears located adjacent the opposite ends of said frame, each pair of said shears consisting of a stationary member and a member reciprocable relative to said stationary member, relative shiftable members carrying said stationary shear members and forming guides for said reciprocable shear members, means for shifting said shiftable member, means interposed between said shiftable member whereby they are actuated simultaneously throughout corresponding distances, pack supporting devices connected to and shiftable with said shiftable members, a pack perforating device arranged intermediate said shears, power actuated mechanism whereby said shears and said perforating device are simultaneously actuated, means for shifting said shiftable members to position upon said supporting devices, and means for automatically imparting an initial removing movement to the pack following trimming thereof.

In testimony whereof, I affix my signature in presence of two subscribing witnesses.

PAUL NELSON.
